(57) **CLAIM**

The ornamental design for a clip for cable management devices, as shown and described.

DESCRIPTION

FIG. 1 is a top perspective view of a clip for cable management devices showing our design;

FIG. 2 is a top view thereof;

FIG. 3 is a bottom view thereof;

FIG. 4 is a side view thereof;

FIG. 5 is an opposing side view thereof;

FIG. 6 is a front view thereof;

FIG. 7 is a rear view thereof;

FIG. 8 is a perspective environmental view of the clip for cable management devices secured to adjacent cable management devices; and,

FIG. 9 is top environmental view thereof.

The broken lines are included for the purpose of illustrating portions of the clip for cable management devices and form no part of the claimed design.
